UNITED STATES PATENT OFFICE.

HOWARD M. BARBER, OF STONINGTON, CONNECTICUT, ASSIGNOR TO C. R. COTTRELL SONS COMPANY, OF NEW YORK, N. Y., A CORPORATION OF NEW JERSEY.

SHEET-DELIVERY APPARATUS FOR PRINTING-MACHINES.

1,073,317.

Specification of Letters Patent. Patented Sept. 16, 1913.

Application filed February 16, 1911. Serial No. 699,611.

To all whom it may concern:

Be it known that I, HOWARD M. BARBER, a citizen of the United States, and resident of Stonington, in the county of New London and State of Connecticut, have invented a new and useful Improvement in Sheet-Delivery Apparatus for Printing-Machines, of which the following is a specification.

The object of this invention is to provide 10 a reciprocating sheet support interposed between a delivery carrier and a sheet feeding tape carrier, the said sheet support being arranged to travel forward with the sheet as the sheet is advanced by the delivery carrier so as to support the rear portion of the sheet until the sheet is about to be released by the delivery carrier, the said sheet support being arranged to be withdrawn from beneath the sheet for permitting the sheet 20 to drop bodily onto the pile of sheets.

This invention is more particularly applicable for use in connection with the sheet delivery apparatus shown, described and claimed in my co-pending application filed 25 June 8, 1908, Serial No. 500878, a sufficient portion of said apparatus being shown and described herein to give a clear understanding of the construction, arrangement and operation of my improved reciprocating 30 sheet support.

In the accompanying drawings, Figure 1 is a view in longitudinal vertical section of portions of a two-revolution cylinder printing machine having my reciprocating 35 sheet support applied thereto, the sheet support being shown at the limit of its return stroke, Fig. 2 is a partial transverse vertical section taken in the plane of the line A—A of Fig. 1, the sheet receiving table 40 and pile of sheets being removed, and Fig. 45 3 is a fragmentary longitudinal vertical section similar to Fig. 1, showing the reciprocating sheet support at the limit of its forward movement over the sheet receiving table.

The form cylinder is denoted by 1 and its impression cylinder by 2. The form cylinder gear 3 is driven from a gear 4 on the drive shaft 5, which shaft may be driven

from a suitable motor 6. The cam shaft 7-50 is driven from the form cylinder 1 through the gears 8, 9. The sheet receiving table is denoted by 10 and the pile of sheets thereon by 11.

The endless sheet delivery carrier is de- 55 noted by 12 and may be driven at the required speed by any desired mechanism not shown herein. The endless delivery carrier may be provided with one or more sets of sheet grippers 13, which are opened by the 60 cams 14 in the usual manner to receive the advance edge of the sheets as they are fed from the sheet feeding tape carrier to be immediately described. These grippers are also arranged to be opened for depositing 65 the sheets onto the table 10 by means not shown herein.

The means for conveying the sheets from the impression cylinder 2 to the sheet de- 70 liver carrier 12 comprises a tape carrier 15 driven from the impression cylinder gear 16 through the intermediate gears 17, 18. The outer ends of the tapes of the tape carrier 15 pass around pulleys 19 located adjacent to the inner end of the endless delivery 75 carrier.

Sheet feeding rolls 20, 21, are provided at the inner end of the tape carrier for engag- 80 ing the sheets as they leave the impression cylinder 2. A positive sheet forwarding de- 85 vice 22 is located intermediate the inner and outer ends of the tape carrier 15, which device is arranged to engage the sheet as it passes along the tape carrier and feed the same to the grippers 13 on the delivery car- 90 rier. The operation of this positive sheet forwarding device is controlled from the cam shaft 7 through a cam 23, bar 24, stud 25, arm 26 and rock shaft 27.

In the arrangement of the parts as herein 90 shown, the endless tape carrier travels at the surface speed of the impression cylinder and at a speed one and one-half times fas- 95 ter than the endless delivery carrier but it is to be understood that this particular relationship in the speed and movement of the several devices is not important to this pres- ent invention and forms no part thereof.

This present invention is directed to the reciprocating sheet support which will now be specifically described.

A series of horizontally arranged sheet supporting racks 28 are mounted to slide forwardly and rearwardly in a plurality of brackets 29 supported upon a cross bar 30 and a rotary cross shaft 31. These racks 28 have an extended support in their brackets 29 and are held in position by any suitable arrangement such, for instance, as giving these bars an undercut sliding engagement with their brackets as will be clearly seen by referring to Fig. 2. These racks 28 are of sufficient length to be projected a considerable distance over the sheet receiving table 10 when at the limit of their forward movement or stroke and will be projected to the sheet feeding endless tape carrier 15 when at the limit of their rearward or return movement or stroke. The means which I have shown for reciprocating this sheet support is as follows:—The rotary shaft 31 has fixed thereto gears 32 meshing with the racks 28. This shaft has further fixed thereto a pinion 33 which meshes with a rack 34 on the outer end of a bar 35, the movement of which bar is controlled by a cam 36, the groove 37 of which cam, in which the stud or roller 38 on the bar 35 is located, being so arranged that the cam will impart a forward movement to the sheet support at a speed corresponding substantially to the speed of the delivery carrier 12 and will impart a rapid return movement to the sheet support for withdrawing it from beneath the sheet in time to permit the sheet to be dropped onto the sheet receiving table 10. The rack 34 of the bar 35 may be held in engagement with the pinion 33 by a roller 39 along which the rack slides.

The operation of the apparatus is as follows:—As the sheet leaves the impression cylinder 2 it is forwarded by the rolls 20, 21, the tape carrier 15 and the positive sheet forwarding device 22 into position to be engaged by the grippers 13 on the sheet, delivery carrier 12. As the sheet is drawn out by the grippers 13 over the sheet receiving table 10, the reciprocating sheet support will also be advanced for supporting the sheet and preventing the center of the sheet from dropping down and dragging along the pile of previously deposited sheets. When the leading edge of the sheet is within a short distance of the point where it is to be released by the grippers 13, the sheet support will commence to withdraw from under the sheet thus leaving the sheet free to fall onto the receiving table as the grippers 13 release the leading edge of the sheet. As has hereinbefore been explained, the withdrawing or return movement of the

sheet support is rapid so as to insure the 65 free fall of the sheet onto the receiving table.

It is evident that changes may be resorted to in the form, construction and arrangement of the several parts without departing from the spirit and scope of my invention; hence I do not wish to limit myself strictly to the structure herein set forth, but

What I claim is:—

1. In a sheet delivery apparatus for printing machines, a sheet receiving table, a delivery carrier arranged to draw the sheet out over the table and then release the sheet, means for feeding the sheet to the delivery carrier and a bodily reciprocating sheet support arranged to travel part way out over the table with the sheet and to be withdrawn from beneath the rear portion of the sheet as it is released by the delivery carrier, for permitting the sheet to fall freely onto the receiving table.

2. In a sheet delivery apparatus for printing machines, a sheet receiving table, an endless delivery carrier having the grippers 90 arranged to engage the advance edge of the sheet and draw the sheet out over the table and then release the sheet, means for feeding the sheet to the delivery carrier grippers and a bodily reciprocating sheet support arranged to travel part way over the table with the sheet and to be withdrawn from beneath the rear portion of the sheet as it is released by the delivery carrier grippers, for permitting the sheet to fall 100 freely onto the receiving table.

3. In a sheet delivery apparatus for printing machines, a sheet receiving table, a relatively fixed endless delivery carrier, a relatively fixed endless tape carrier for feeding sheets thereto, a bodily reciprocating sheet support interposed between the delivery carrier and tape carrier and means for moving the sheet support partway out over the table with the sheet and for withdrawing the sheet support from beneath the rear portion of the sheet to permit it to be delivered onto the table.

4. In a sheet delivery apparatus for printing machines, a sheet receiving table, a relatively fixed endless delivery carrier, a relatively fixed endless tape carrier for feeding sheets thereto, a bodily reciprocating sheet support interposed between the delivery carrier and tape carrier, and means for moving the sheet support with the sheet out over the receiving table at a certain speed and for withdrawing the sheet support at a higher speed.

5. In a sheet delivery apparatus for printing machines, a sheet receiving table, a sheet delivery device, means for feeding sheets thereto and a reciprocating sheet support

interposed between the delivery device and the sheet feeding means, comprising a plurality of horizontally arranged racks, gears meshing with said racks, a pinion fixed to 5 rotate with said gears and a cam operated bar having a rack meshing with said pinion.

In testimony, that I claim the foregoing as my invention, I have signed my name in

presence of two witnesses, this thirteenth day of February A. D. 1911. 10

HOWARD M. BARBER
